UNITED STATES PATENT OFFICE

131,316

DESIGN FOR A LABORATORY APPARATUS HAND TRUCK

Morris Dann, Cleveland, Ohio

Application April 15, 1941, Serial No. 100,394

Term of patent 14 years

To all whom it may concern:

Be it known that I, Morris Dann, a citizen of the United States, residing at Cleveland, in the county of Cuyahoga and State of Ohio, have invented a new, original, and ornamental Design for a Laboratory Apparatus Hand Truck, of which the following is a specification, reference being had to the accompanying drawing, forming part thereof, wherein:

I claim:

The ornamental design for a laboratory apparatus hand truck, substantially as shown.

MORRIS DANN.
